(57) **CLAIM**

The ornamental design for a gas feeder for endoscope, as shown and described.

DESCRIPTION

FIG. 1 is a top, front and side perspective view of a gas feeder for endoscope showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof; and,
FIG. 7 is a left side elevational view thereof.
In the drawings, the broken lines depict environmental subject matter only and form no part of the claimed design.
